UNITED STATES PATENT OFFICE.

GUSTAV H. STAHL, OF MENOMONIE, WISCONSIN, ASSIGNOR TO PROGRESS MANUFACTURING COMPANY, A COPARTNERSHIP CONSISTING OF GUSTAV H. STAHL AND RICHARD GOERNER, OF ERIE, PENNSYLVANIA.

TOOL HOLDER.

1,422,491.

Specification of Letters Patent. Patented July 11, 1922.

Application filed October 24, 1918, Serial No. 259,580. Renewed November 12, 1921. Serial No. 514,827.

To all whom it may concern:

Be it known that I, GUSTAV H. STAHL, a citizen of the United States, and a resident of the city of Menominie, county of Dunn, 5 and State of Wisconsin, have invented certain new and useful Improvements in Tool Holders, of which the following is a specification.

My invention relates to improvements in tool holders and has for its object the provision of an improved tool holder for use in lathes and the like, arranged and adapted to improve the quality of work which may be performed thereon.

Other objects will appear hereinafter.

The invention consists in the combinations and arrangements of parts hereinafter described and claimed.

The invention will be best understood by reference to the accompanying drawings forming a part of this specification, and in which,

Fig. 1, is a longitudinal section of a tool holder embodying the invention,

Fig. 2, a top plan view of the same,

Fig. 3, a side view of the same,

Fig. 4, a transverse section of the same, and

Fig. 5, a perspective view of a stiffening member employed in the tool holder.

The preferred form of construction, as illustrated in the drawings, comprises a tool holding bar 6 having a socket at its forward end for the reception of any usual or desired

35 form or cutting tool 7, and a securing screw 8, as shown. A notch 9 is provided in the bar 6 immediately to the rear of the tool 7 and extending upwardly from the lower edge of said tool well above the same to give resiliency to the connection between the tool

40 socket and the body of the bar. To further increase this resiliency, a spring member 10, in substantially inverted U-shape and chan-

45 neled to fit the upper end of notch 9 and embrace the sides of the bar 6 is provided, which also serves to stiffen the bar against lateral deflections or "wiggling."

45 A stiffening block 11 is loosely inserted in the lower portion of the notch 9, said stiffening block being in ex- 50 aggerated I-form in horizontal section and provided with flanges embracing the sides of the bar, whereby the vertical resiliency of said bar is not impaired, but lateral deflec- 55 tions or wiggling thereof is prevented. A

yieldable plunger 12 is mounted in the rear 55 of bar 6 to span the notch 9 and bear against the forward wall thereof, block 11 being provided with a central opening 13 to permit of the free passage of said plunger. A coiled spring 14 is imprisoned in the bar 6 to the 60 rear of plunger 12, and an adjusting screw 15 is provided for adjusting the tension of said spring and whereby the resiliency of the construction is further augmented and rendered adjustable, as will be readily understood.

In use, the tool holder is mounted in the tool rest of a lathe or the like, in the usual manner, and various tools 7 mounted therein as desired. Owing to the resilient character 70 of the tool holder thus provided, nice work, such as the cutting of threads of any size, may be readily and economically done without causing the cutting tool to dig into the work or tear the thread, as is usual with solid 75 tools. Any desired shape or character of tool or cutter may be employed, and a round tool may be used to advantage in cutting square threads, without interfering with the angle. By adjusting the tension of the spring 14, 80 greater stiffness may be imparted to the tool holder for the "roughing" of threads or other work, and this tension may be decreased for the finishing operation, thus permitting of 85 doing very fine and accurate work. The specific form and arrangement of parts is a simple and efficient one for the purpose.

While I have illustrated and described the preferred form of construction for carrying my invention into effect, this is capable of 90 variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A construction of the class described comprising a holder bar; a tool socket at one end of said bar, there being a notch in said bar to give resiliency thereto; and a spring-held plunger in said bar spanning said notch, 105 substantially as described.

2. A construction of the class described comprising a holder bar; a tool socket at one

end of said bar, there being a notch in said bar to give resiliency thereto; and a stiffening block loosely inserted in said notch adjacent the open end thereof and slidably engaging opposite sides of said bar, substantially as described.

3. A construction of the class described comprising a holder bar; a tool socket at one end of said bar, there being a notch in said bar to give resiliency thereto; a substantially U-shaped spring in said notch permitting yielding of said bar; and a stiffening member located in said notch adjacent the open end thereof and engaging the sides of said bar, substantially as described.

4. A construction of the class described comprising a holder bar; a tool socket at one end of said bar, there being a notch in said bar to give resiliency thereto; a substantially U-shaped spring in said notch; and a spring-held plunger in said bar spanning said notch, substantially as described.

5. A construction of the class described comprising a holder bar; a tool socket at one end of said bar, there being a notch in said bar to give resiliency thereto; a substantially U-shaped spring in said notch; a stiffening member located in said notch and engaging the sides of said bar; and a spring-held plunger in said bar spanning said notch, substantially as described.

6. A construction of the class described

comprising a bar having a tool socket at one end; a notch in said bar immediately beyond said tool socket and extending from the lower edge thereof upwardly beyond said socket; a substantially U-shaped channeled spring member fitting the upper end of said socket and embracing the sides of said bar; a stiffening member in substantially exaggerated I-form fitting loosely within the lower portion of said notch and having flanges embracing the sides of said bar; a yieldable plunger mounted in the rear portion of said bar and spanning said notch, there being a central opening in said stiffening member permitting of the free passage of said plunger; a spring in said bar bearing against the rear end of said plunger; and a screw for adjusting the tension of said spring, substantially as described.

7. A construction of the class described comprising a bar; a tool socket at one end of said bar; a notch in said bar to the rear of said tool socket; and a spring-held plunger mounted in the rear of said bar and spanning said notch, substantially as described.

In testimony whereof I have signed my name to this specification in the presence of two subscribing witnesses.

GUSTAV H. STAHL.
